DESIGN FOR A HOUSE TRAILER

Rex R. Anderson, Marshall, Mich.

Application October 31, 1940, Serial No. 96,220

Term of patent 14 years

To all whom it may concern:

Be it known that I, Rex R. Anderson, a citizen of the United States, residing at Marshall, in the county of Calhoun and State of Michigan, have invented a new, original, and ornamental Design for a House Trailer, of which the following is a specification, reference being had to the accompanying drawings forming part thereof.

Figure 1 is a side perspective view of a house trailer embodying my new design. The other side is the same except that the door is omitted.

Figure 2 is a side perspective view of a house trailer embodying my new design, but with parts broken away to show the interior of the trailer.

Figure 3 is a view of the interior of the house trailer looking towards the rear from about the center.

Figure 4 is a view of the interior of the house trailer looking towards the front from about the center.

The characteristic features of my design reside in the interior portions as shown in full lines in Figures 2, 3, and 4 of the drawings.

I claim:

The ornamental design for a house trailer, substantially as shown and described.

REX R. ANDERSON.
